REFRIGERATION CONTROL SYSTEM

Alwin B. Newton, Minneapolis, Minn., assignor
to Minneapolis-Honeywell Regulator Company,
Minneapolis, Minn., a corporation of Delaware

Application October 27, 1939, Serial No. 301,606

22 Claims. (Cl. 62—4)

This invention relates to a control system for a refrigerating apparatus having a plurality of evaporators for cooling a space or compartment and a compressor for circulating refrigerant through the evaporators.

The prime object of this invention is to control the flow of refrigerant through the evaporators in such a manner as to maintain desired temperature or other conditions in the space and to defrost intermittently the evaporators. In carrying out this object of the invention, a valve is located between each evaporator and the suction side of the compressor for establishing or interrupting communication therebetween. Each valve is controlled by the frost condition of its associated evaporator, such as by the temperature of or the pressure within the evaporator, and by a thermostat responsive to the temperature in the space or compartment. When the valves are closed the pressure in the evaporators increases to allow defrosting of the evaporators. When the thermostat calls for cooling the valves are opened providing their associated evaporators have defrosted and are closed when the thermostat is satisfied. Thus, desired temperature conditions are maintained in the space or compartment and the evaporators are individually and intermittently defrosted.

Another object of this invention is to operate sequentially the valves by the space or compartment thermostat so that when the temperature is low all of the valves are closed and as the temperature increases first one valve is opened and then another as the temperature increases further.

A further object of this invention is to provide air circulating means for circulating air over the evaporators and to operate the air circulating means at high speed when the evaporators are performing a cooling function and to operate the air circulating means at slow speed when the evaporators are defrosting.

Another object of this invention is to cause operation of the compressor when any of the valves are open to cause their associated evaporators to perform a cooling function and to increase the compressor speed as more valves open.

Still another object of this invention is to close the valves and stop operation of the compressor when the suction pressure decreases to a predetermined low value.

A further object of this invention is to prevent opening of the valves and starting of the compressor unless the head pressure is below a predetermined low value and to close the valves

after they are once opened and stop the compressor after it has once started when the head pressure increases to a predetermined high value.

A still further object of this invention is to provide overload cut-out means in the high speed and low speed circuits of the compressor motor for closing the valves and stopping the compressor when an overload condition occurs in either of these circuits.

Other objects and advantages will become apparent to those skilled in the art upon reference to the specification, claims and drawing, in which is diagrammatically disclosed the preferred form of this invention.

The space or compartment to be conditioned or cooled is designated at 10. Cooling coils in the form of evaporators 11 and 12 are utilized for cooling the space 10. A fan 13 operated by a two-speed motor 14 withdraws air from the space 10 through a duct 15, passes this air over the evaporator 11 and discharges it in a cooled condition through a duct 16 into the space 10. In a like manner, a fan 17 operated by a two-speed motor 18 withdraws air from the space 10 through a duct 19, passes this air over the evaporator 12 and discharges the cooled air through a duct 20 into the space 10. While the evaporators 11 and 12 have been shown exterior to the space 10, these evaporators may be located within the space 10.

Refrigerant is supplied to the evaporators 11 and 12 by a refrigerating apparatus generally designated at 22. The refrigerating apparatus may comprise a compressor 23 operated by a two-speed electric motor 24. Compressed refrigerant passes from the compressor 23 through a high pressure line 25 into a condenser 26. Condensed refrigerant flows through a liquid line 27 from the condenser 26 and through branch liquid lines 28 and 29 to the evaporators 11 and 12, respectively. Evaporated refrigerant is withdrawn from the evaporators 11 and 12 through branch suction lines 30 and 31 and through suction line 32 by the compressor 23. The flow of refrigerant into the evaporator 11 may be regulated by a thermostatic expansion valve 33 having a bulb 34 responsive to the temperature of the refrigerant leaving the evaporator 11. In a like manner the flow of refrigerant to the evaporator 12 may be controlled by a thermostatic expansion valve 35 having a bulb 36 responsive to the temperature of the refrigerant leaving the evaporator 12. While only two evaporators 11 and 12 have been shown for purposes of illus-

tration, any number may be utilized within the contemplation of this invention.

A solenoid valve 37 is located in the branch suction line 30 and when this solenoid valve 37 is deenergized communication between the evaporator 11 and the suction side of the compressor 23 is interrupted. When the solenoid valve 37 is energized the evaporator 11 is placed in communication with the suction side of the compressor. A solenoid valve 38 is also located in the branch suction line 31 to interrupt communication between the evaporator 12 and the suction side of the compressor 23 when it is deenergized and to cause communication between the evaporator 12 and the suction side of the compressor 23 when it is energized. When the valve 37 is closed the pressure within the evaporator 11 is allowed to build up to permit defrosting of the evaporator 11. Similarly, when the valve 38 is closed the pressure in the evaporator 12 is permitted to rise to defrost the evaporator 12.

Cooling water is supplied to the condenser 26 through a supply pipe 40 and is discharged from the condenser 26 through a discharge pipe 41. A valve 42 controls the rate of flow of cooling water to the condenser 26 and this valve is connected by a pipe 43 to the high pressure line 25 so that this valve is operated in accordance with changes in pressure in the condenser 26. Upon an increase in condenser pressure the valve 42 is gradually moved towards an open position to increase the supply of cooling water to the condenser and upon a decrease in pressure the valve 42 is gradually moved towards a closed position to throttle the supply of cooling water to the condenser 26. For purposes of illustration it is assumed that the valve 42 is so arranged that it maintains the pressure in the condenser 26 between 135 pounds and 140 pounds. The two-speed motor 24 which operates the compressor 23 may be controlled by a two-speed starter generally designated at 45. The starter 45 is in turn controlled by two relays 46 and 47, the arrangement being such that when either relay 46 or 47 is energized the starter 45 is controlled to operate the compressor at low speed and when both of the relays 46 and 47 are energized the starter 45 is controlled to operate the compressor 23 at high speed. The relay 46 is controlled by a combined suction pressure and head pressure responsive controller 48 and the relay 47 is controlled by a combined suction pressure and head pressure responsive controller 49. A two-stage thermostat 50 responsive to the temperature within the space or compartment 10 also controls the operation of the suction pressure and head pressure responsive controllers 48 and 49. The suction pressure and head pressure responsive controller 48 also controls the solenoid valve 37 and a relay 51 which controls the operation of the two-speed fan motor 14. Likewise the suction pressure and head pressure responsive controller 49 also controls the solenoid valve 38 and controls a relay 52 which in turn controls the operation of the two-speed fan motor 18.

The suction pressure and head pressure responsive controller 48 may be of the type shown and described in application Serial No. 196,447, filed March 17, 1938, by Albert L. Judson and Carl G. Kronmiller. For purposes of illustration in this application this controller is shown to comprise a bellows 59 connected by a pipe 60 to the branch suction line 30 between the solenoid valve 37 and the evaporator 11. Accordingly the bellows 59 is operated in response to the pressure existing with-

in the evaporator 11. The bellows 59 operates a lever 61 pivoted on a fulcrum member 62 against the action of an adjustable tension spring 63. By suitably adjusting the tension in the spring 63 the pressure setting of this portion of the controller may be varied at will. The lever 61 operates contacts 64 and 65 and while these contacts 64 and 65 are electrically coupled together they are insulated from the lever 61. The contact 64 is adapted to engage and disengage a contact member 66 carried by a terminal 67 and the contact 65 is adapted to engage and disengage a contact member 68 carried by a terminal 69. The contact members 66 and 68 are urged into engagement with concentrically located independently adjustable cams 70 and 71. By independently rotating the cams 70 and 71 the contact members 66 and 68 may be independently positioned with respect to the contacts 64 and 65. For purposes of illustration it is assumed that when the pressure within the evaporator 11 rises to 15 lbs. the contact 64 engages the contact 66 and when the pressure rises to 35 lbs. the contact 65 engages the contact member 68. Upon a decrease in pressure in the evaporator 11 the contact 65 first disengages the contact member 68 at 35 lbs. and then the contact member 64 disengages the contact member 66 at 15 lbs. It is here assumed that the pressure in the evaporator 11 may rise to 35 lbs. only after the evaporator 11 has defrosted.

The suction pressure and head pressure responsive controller 48 may also comprise a bellows 73 connected by a pipe 74 to the liquid line 27 so that the bellows 73 is responsive to the pressure on the high pressure side of the refrigerating apparatus. The bellows 73 operates a lever 75 fulcrumed on a fulcrum member 76 against the action of an adjustable tension spring 77. By suitably adjusting the tension spring 77 the pressure setting of this portion of the controller may be adjusted at will. The lever 75 adjustably carries an abutment member 78 preferably made of insulating material. The abutment member 78 is provided with two abutment surfaces 79 and 80. The abutment surface 79 is adapted to engage a contact member 81 carried by a terminal 82 to move the contact member 81 out of engagement with a contact 83. The abutment surface 80 is adapted to engage a contact member 84 carried by the terminal 69 for moving the contact member 84 out of engagement with a contact 85. For purposes of illustration it is assumed that as the pressure on the high pressure side of the refrigerating apparatus rises to 140 lbs. the contact member 84 is moved out of engagement with the contact 85 and when the pressure rises to 180 lbs. the contact member 81 is moved out of engagement with the contact 83. Upon a decrease in head pressure the contact member 81 first engages the contact 83 at 180 lbs. and then the contact member 84 engages the contact 85 at 140 lbs.

The suction pressure and head pressure responsive controller 48 also includes a relay having an operating coil 87 for operating bridge members 88 and 89. When the operating coil 87 is energized the bridge member 88 is moved into engagement with contacts 90 and 91 and the bridge member 89 is moved into engagement with contacts 92 and 93. When the operating coil 87 is de-energized the bridge members 88 and 89 are moved out of engagement with their respective contacts by means of springs, gravity or other means, not shown. The controller 48 is also pro-

vided with a terminal 94 to facilitate external connections.

The suction pressure and head pressure responsive controller 49 which responds to the pressure in the evaporator 12 and to the pressure in the liquid line 27 is exactly the same as the suction pressure and head pressure responsive controller 48 and therefore like reference characters primed have been utilized to designate like parts. A further description of the construction of the controller 49 is therefore not considered necessary.

The two-stage thermostat 50 may comprise a bellows 96 charged with a volatile fluid for operating a lever 97 against the action of an adjustable tension spring 98. The lever 97 operates a mercury switch 99 having electrodes 100, 101 and 102. For purposes of illustration it is assumed that when the temperature within the compartment or space 10 rises to 40° the mercury switch 99 is tilted to cause bridging of the electrodes 100 and 101 and when the temperature rises to 42° the mercury switch 99 is tilted to cause bridging of the electrodes 100, 101 and 102. When the temperature within the compartment or space 10 decreases to 40° the switch 99 is tilted to bridge only the electrodes 100 and 101 and when the temperature decreases to 38° none of the electrodes 100, 101 or 102 are bridged.

The relay 51 which controls the operation of the two-speed fan motor 14 may comprise an operating coil 104 for operating a switch arm 105 with respect to contacts 106 and 107. The parts are so arranged that when the operating coil 104 is energized the switch arm 105 is moved into engagement with the contact 107 and when the operating coil 104 is deenergized the switch arm 105 is moved into engagement with the contact 106 by means of springs, gravity or other means, not shown.

The relay 52 which controls the operation of the two-speed fan motor 18 is exactly the same as the relay 51 and therefore like reference characters primed have been utilized for like parts. Accordingly a further description of the relay 52 is not considered necessary.

The two-speed starter 45 for the two-speed compressor motor 24 may comprise an operating coil 110 for operating a switch arm 111 with respect to a contact 112. When the operating coil 110 is energized the switch arm 111 is moved into engagement with the contact 112 and when the operating coil 110 is deenergized the switch arm 111 is moved out of engagement with the contact 112 by means of springs, gravity or other means, not shown. The switch arm 111 and the contact 112 control the starting and stopping of the compressor motor 24. The two-speed starter 45 also includes an operating coil 113 for operating a switch arm 114 with respect to contacts 115 and 116. When the operating coil 113 is energized the switch arm 114 is moved into engagement with the contact 115 to operate the compressor motor 24 at high speed and when the operating coil 113 is deenergized the switch arm 114 is moved into engagement with the contact 116 by means of springs, gravity or other means, not shown, to operate the compressor motor 24 at low speed providing the switch arm 111 is engaging the contact 112. A heater element 117 located in the low speed circuit of the compressor motor 24 operates upon an overload condition in this circuit to flex a bimetallic element 118 carried by a terminal 119 for moving the bimetallic element 118 out of engagement

with a contact 120. The heater 117, bimetallic element 118 and contact 120 therefore form an overload cut-out arrangement responsive to overload conditions in the low speed circuit of the compressor motor 24. A heater 121 located in the high speed circuit of the compressor motor 24 operates to heat a bimetallic element 122 carried by a terminal 123 for flexing the bimetallic element 122 out of engagement with a contact 124 upon the occurrence of an overload condition in the high speed circuit of the compressor motor 24. The heater 121, the bimetallic element 122 and the contact 124 therefore form an overload cut-out responsive to overload conditions in the high speed circuit of the compressor motor 24.

The relay 46 may comprise an operating coil 130 for operating switch arms 131 and 132 with respect to contacts 133 and 134. When the operating coil 130 is energized the switch arms 131 and 132 are moved into engagement with contacts 133 and 134, respectively, and when the operating coil 130 is deenergized the switch arms 131 and 132 are moved out of engagement with their respective contacts by means of springs, gravity, or other means, not shown.

The relay 47 is exactly the same as the relay 46 and therefore like reference characters primed have been utilized for designating like parts. There is only one difference between the relay 47 and the relay 46 and that is that the switch arms 131' and 132' of the relay 47 are electrically connected together by a conductor 135 while the corresponding switch arms of the relay 46 are not electrically connected together.

Power is supplied to the various control devices, relays, valves, fan motors and compressor motor by means of line wires 139 and 140 leading from some source of power, not shown.

With the parts in the position shown in the drawing everything is shut down. Assume now that the temperature within the space or compartment 10 rises to 40° to bridge the electrodes 100 and 101, that the pressure in the evaporator 11 rises to 35 lbs. following defrosting of the evaporator 11 to move the contacts 64 and 65 into engagement with the contact members 66 and 68 and that the pressure in the condenser 28 is below 140 lbs. to cause the contact members 81 and 84 to engage the contacts 83 and 85. Under these conditions a starting circuit is completed from the line wire 139 through wires 141 and 142, electrodes 100 and 101 of the mercury switch 99, wire 143, contact 83, contact member 81, terminal 82, conductor 144, terminal 67, contact member 66, contacts 64 and 65, contact members 68 and 84, contact 85, conductor 145, contact 91, conductor 146, operating coil 87, conductor 147, terminal 94, wires 148 and 149, terminal 119, bimetallic element 118, contact 120, conductor 150, contact 124, bimetallic element 122, terminal 123 and wire 151 back to the other line wire 140. Completion of this starting circuit energizes the operating coil 87 to move the bridge members 88 and 89 into engagement with their respective contacts.

Movement of the bridge member 88 into engagement with its contacts 90 and 91 completes a maintaining circuit which may be traced from the line wire 139 through wires 141 and 142, electrodes 100 and 101 of the mercury switch 99, wire 143, contact 83, contact member 81, terminal 82, conductor 144, terminal 67, contact member 66, contact 64, conductor 152, contact 90, bridge member 88, contact 91, conductor 146, operat-

ing coil 87, conductor 147, terminal 94, wires 148 and 149, terminal 119, bimetallic element 118, contact 120, conductor 150, contact 124, bimetallic element 122, terminal 123 and wire 151 back to 153, contact 83', contact member 81', terminal 82', conductor 154, terminal 67', contact member 66', contact 64', conductor 159, contact 90', bridge member 88', contact 91', conductor 145, operating coil 87', conductor 157, terminal 94', wires 158 and 149, terminal 119, bimetallic element 118, contact 120, conductor 150, contact 124, bimetallic element 122, terminal 123 and wire 151 back to the other line wire 140. Completion of this circuit maintains the operating coil 87' energized until either the temperature within the space or compartment 10 decreases to 38° or until the pressure within the evaporator 11 decreases to 15 lbs. or until the pressure on the high pressure side of the refrigerating apparatus increases to 180 lbs. Upon the occurrence of any of these conditions the operating coil 87' is deenergized and cannot again be reenergized until the above mentioned starting circuit is completed. As pointed out above, this starting circuit can be completed only when the temperature within the compartment or space 10 rises to 40°, the pressure in the evaporator 11 rises to 35 lbs., and the pressure on the high pressure side of the refrigerating apparatus decreases to 140 lbs. It is here noted that the overload cut-outs in the two-speed starter 45 are both included in the starting and maintaining circuits outlined above so that if an overload condition should occur in either the low speed circuit or the high speed circuit of the compressor motor 24 the operating coil 87' will be deenergized.

Summing up, the operating coil 87' of the controller 48 may be energized only when the temperature in the space 10 rises to 38°, the pressure in the evaporator 11 rises to 35 lbs., and the pressure on the high pressure side decreases to 140 lbs. and after the operating coil 87' has thus been energized it will remain energized until either the temperature within the space 10 decreases to 38° or the pressure in the evaporator 11 decreases to 15 lbs. or the pressure on the high pressure side of the refrigerating apparatus increases to 180 lbs. If an overload condition occurs in either the slow speed or high speed circuits of the compressor motor 24 the operating coil 87' of the controller 48 is deenergized.

Assume now that the temperature within the space or compartment 10 rises to 42° to cause bridging of electrodes 100, 101 and 102, that the pressure in the evaporator 12 rises to 35 lbs. to cause the contact 64' and 65' to engage the contact members 66' and 68' and that the pressure on the high pressure side of the refrigerating apparatus is below 140 lbs., to cause the contact members 81' and 84' to engage the contacts 83' and 85'. Under these conditions a starting circuit for the operating coil 87' of the controller 49 is completed and this starting circuit may be traced from the line wire 139 through wires 141 and 142, electrodes 100 and 102 of the mercury switch 99, wire 153, contact 83', contact member 81', terminal 82', conductor 154, terminal 67', contact member 66', contacts 64' and 65', contact members 68' and 84', contact 85', conductor 155, contact 91', conductor 156, operating coil 87', conductor 157, terminal 94', wires 158 and 149, terminal 119, bimetallic element 118, contact 120, conductor 150, contact 124, bimetallic element 122, terminal 123 and wire 151 back to the other line wire 140. Completion of this starting circuit energizes the operating coil 87' of the controller 49 to move the bridge member 88' and 89' into engagement with their respective contacts.

Movement of the bridge member 88' into engagement with its contacts 90' and 91' completes a maintaining circuit which may be traced from the line wire 139 through wires 141 and 142, electrodes 100 and 102 of the mercury switch 99, wire

153, contact 83', contact member 81', terminal 82', conductor 154, terminal 67', contact member 66', contact 64', conductor 159, contact 90', bridge member 88', contact 91', conductor 145, operating coil 87', conductor 157, terminal 94', wires 158 and 149, terminal 119, bimetallic element 118, contact 120, conductor 150, contact 124, bimetallic element 122, terminal 123 and wire 151 back to the other line wire 140. Completion of this circuit maintains the operating coil 87' energized until either the temperature within the space or compartment 10 decreases to 40° or the pressure in the evaporator 12 decreases to 15 lbs. or the pressure on the high pressure side of the refrigerating apparatus increases to 180 lbs. 15

Summing up, the operating coil 87' of the controller 49 is energized only when the temperature within the compartment 10 rises to 42°, the pressure in the evaporator 12 rises to 35 lbs. and the head pressure decreases to 140 lbs. and after the operating coil 87' is once energized it is maintained energized until either the temperature within the compartment or space 10 decreases to 40° or the pressure in the evaporator 12 decreases to 15 lbs. or until the head pressure 25 increases to 180 lbs. It is here noted that the two overload cut-outs in the two-speed starter 45 are also connected in both the starting and maintaining circuits of the controller 49 so that upon the occurrence of an overload condition in 30 either the low speed or high speed circuits of the compressor motor 24 the operating coil 27' of the controller 49 is deenergized.

When the operating coil 87' of the controller 48 is energized in the manner pointed out above 35 to move the bridge member 89 into engagement with the contacts 92 and 93, a circuit is completed from the line wire 139 through wire 165, contact 92, bridge member 89, contact 93, wires 166, 167 and 168, solenoid valve 37, and wires 40 169, 170 and 171 back to the other line wire 140. Completion of this circuit energizes the solenoid valve 37 to establish communication between the evaporator 11 and the suction side of the compressor 23. When the operating coil 87' 45 is deenergized this circuit is interrupted to close the solenoid valve 37 to interrupt communication between the evaporator 11 and the suction side of the compressor 23. Thus whenever the temperature within the space 10 rises to 38° and 50 the evaporator 11 has defrosted to allow the pressure therein to rise to 35 lbs. and the head pressure has decreased to 140 lbs. the solenoid valve 37 is opened to cause the evaporator 11 to perform a cooling function. When either the 55 temperature within the space 10 decreases to 38°, or the pressure in the evaporator 11 decreases to 15 lbs., or the head pressure increases to 180 lbs., the solenoid valve 37 is closed to interrupt communication between the evaporator 11 and the 60 suction side of the compressor 23. Thus the evaporator 11 no longer performs a cooling function and is allowed to defrost. After the evaporator 11 has defrosted the valve 37 is again opened to cause the evaporator 11 to perform a 65 cooling function providing the thermostat 50 is demanding cooling and the pressure on the high pressure side of the refrigerating apparatus has decreased to 140 lbs.

When the operating coil 87' of the controller 48 70 is energized to cause the bridge member 89 to engage the contacts 92 and 93 a circuit is completed from the line wire 139 through wire 165, contact 92, bridge member 89, contact 93, wires 166, 167 and 173, operating coil 104 of the relay 75

51 and wires 174, 170 and 171 back to the other line wire 140. Completion of this circuit energizes the operating coil 104 of the relay 51 to move the switch arm 105 into engagement with the contact 107. When this occurs a high speed circuit for the fan motor 14 is completed and this circuit may be traced from the line wire 139, through wires 141 and 176, switch arm 105, contact 107, wire 177, fan motor 14 and wires 178, 10 179 and 171 back to the other line wire 140. Thus the fan 13 is operated at high speed whenever the operating coil 87 of the controller 48 is energized. When the operating coil 87 is deenergized the circuit through the operating coil 104 15 of the relay 51 is broken to cause the switch arm 105 to engage the contact 106 to complete a low speed circuit through the fan motor 14 which may be traced from the line wire 139 through wires 141 and 176, switch arm 105, contact 106, wire 180, fan motor 14 and wires 178, 179 and 171 20 back to the other line wire 140. It will thus be seen that when the evaporator 11 is operating to cool the space 10 the fan 13 is operated at high speed to circulate a maximum amount of cold air into the space 10. When, however, the operating coil 87 of the controller 48 is deenergized so that the valve 37 is closed to cause defrosting of the evaporator 11 the fan 13 is operated at low speed during this defrosting cycle. 25 This will effectively prevent undue heating of the space 10 during the defrosting cycle. If desired the fan may be operated in an on and off manner instead of the two speed manner as explained.

30 When the operating coil 87' of the controller 49 is energized to move the bridge member 89' into engagement with the contacts 92' and 93' a circuit is completed from the line wire 139 through wire 182, contact 92', bridge member 89', contact 93', wires 183, 184 and 185, solenoid valve 38 and wires 186, 187 and 171 back to the other line wire 140. Completion of this circuit energizes the solenoid valve 38 to establish communication between the evaporator 12 and the suction side of the compressor 23 whereupon the evaporator 12 performs a cooling function. When the operating coil 87' is deenergized this circuit is broken and the solenoid valve 38 is closed to interrupt communication between the evaporator 12 and the suction side of the compressor 23 whereupon the evaporator 12 is placed on the defrosting cycle. When the operating coil 87' is energized another circuit is completed from the line wire 39 through wire 182, contact 92', bridge member 89', contact 93', wires 183, 184 and 188, operating coil 104' of the relay 52 and wires 189, 187 and 171 back to the other line wire 140. Completion of this circuit energizes the operating coil 104' to move the switch arm 105' into engagement with the contact 107' to complete a high speed circuit for the fan motor 18 which may be traced from the line wire 139 through wires 141 and 191, switch arm 105', contact 107', wire 192, fan motor 18 and wires 193, 179 and 171 back to the other line wire 140. Thus the fan 17 is operated at high speed while the evaporator 12 is performing a cooling function. When the operating coil 87' of the controller 49 is deenergized the circuit through the operating coil 104' of the relay 52 is broken whereupon the switch arm 105' engages the contact 106' to complete a slow speed circuit for the fan motor 18 which may be traced from the line wire 139 through wires 141 and 191, switch arm 105', contact 106', wire 194, 70 fan motor 18 and wires 193, 179 and 171 back to

the other line wire 140. Thus when the evaporator 12 is on a defrosting cycle the fan 17 is operated at slow speed. It is therefore seen that the solenoid valve 38 and the fan motor 18 are operated in exactly the same way as the solenoid valve 37 and the fan motor 14 are operated, the only distinction being that the solenoid valve 38 is opened and the fan 17 is placed on high speed operation when the temperature within the space 10 rises to 42° while the solenoid valve 37 is 10 opened and the fan 13 is placed on high speed operation when the temperature within the space 10 rises to 40°. Thus a two-stage operation is obtained. If desired, the two valves 37 and 38 and the two fans 13 and 17 could be operated at 15 the same temperature for single stage operation.

When the operating coil 87 of the controller 48 is energized still another circuit is completed from the line wire 139 through wire 165, contact 92, bridge member 89, contact 93, wires 166 and 20 200, operating coil 130 of the relay 46 and wire 201 back to the other line wire 140. Completion of this circuit energizes the operating coil 130 to move the switch arms 131 and 132 into engagement with contacts 133 and 134. When the operating coil 87' of the controller 49 is energized a circuit is completed from the line wire 139 through wire 182, contact 92', bridge member 89', contact 93', wires 183 and 202, operating coil 130' and wire 203 back to the other line wire 140. 30 Completion of this circuit energizes the operating coil 130' of the relay 47 to move the switch arms 131' and 132' into engagement with the contacts 133' and 134'.

When the operating coil 130 is energized to 35 move the switch arm 131 into engagement with the contact 133 a circuit is completed from the line wire 139, through wire 205, contact 133, switch arm 131, wires 206 and 207, operating coil 110 and wires 208 and 209 back to the other line 40 wire 140. Thus when the relay 46 is energized the operating coil 110 of the two-speed starter 45 is energized. When the operating coil 130' of the relay 47 is energized to move the switch arm 131' into engagement with the contact 133', a 45 circuit is completed from the line wire 139 to wire 110, contact 133', switch arm 131', wires 211 and 207, operating coil 110 and wires 208 and 209 back to the other line wire 140. Thus when the relay 47 is energized a circuit is also completed 50 through the operating coil 110 of the two-speed starter 45. In other words, the relays 46 and 47 are arranged in parallel for controlling the energization of the operating coil 110 of the two-speed starter 45 so that when either of these relays is energized the operating coil 110 of the two-speed starter 45 is energized.

When the operating coil 110 of the two-speed starter 45 is energized to move the switch arm 111 into engagement with the contact 112 a low 60 speed circuit for the compressor motor 24 is completed and this circuit may be traced from the line wire 139 through wire 213, switch arm 111, contact 112, wire 214, switch arm 114, contact 116, wire 215, heater 117, wire 216, compressor 65 motor 24 and wire 217 back to the other line wire 140. Accordingly when either relay 46 or 47 is energized the compressor motor 24 and hence the compressor 23 are operated at low speed.

When both relays 46 and 47 are energized a 70 circuit is completed from the line wire 139 through wire 210, contact 133', switch arm 131', conductor 135, switch arm 132', contact 134', wire 220, contact 134, switch arm 132, wire 221, operating coil 113, and wire 209 back to the other line 75

wire 140. Completion of this circuit energizes the operating coil 113 of the two-speed starter 45 to move the switch arm 114 into engagement with the contact 115 to complete a high speed circuit 5 for the compressor motor 24. This high speed circuit may be traced from the line wire 139 through wire 213, switch arm 111, contact 112, wire 214, switch arm 114, contact 115, wire 223, heater 121, wire 224, compressor motor 24, and 10 wire 217 back to the other line wire 140. Accordingly when both relays 46 and 47 are energized the compressor motor 24 is operated at high speed.

The operation of the complete system may be 15 summarized briefly as follows:

When the space temperature decreases to 38°, the compressor 23 is stopped, the solenoid valves 37 and 38 are closed to allow the evaporators 11 and 12 to defrost and the fans 13 and 17 are operating at low speed to assist the defrosting of the 20 evaporators.

When the space temperature increases to 40° and providing the evaporator 11 has defrosted and the head pressure is below 140 lbs. the solenoid valve 37 is opened to cause the evaporator 11 to perform a cooling function, the fan 13 is operated at high speed, and the compressor 23 is operated at low speed. The solenoid valve 37 then remains open, the fan 13 remains operating 30 at high speed and the compressor 23 remains operating at low speed until either the temperature in the space 10 decreases to 38° or the pressure in the evaporator 11 decreases to 15 lbs. or the head pressure increases to 180 lbs.

If while the evaporator 11 is performing a cooling function as outlined immediately above the load should increase to cause the space temperature to rise to 42° and providing the evaporator 12 has defrosted and the head pressure 40 is below 140 lbs., then the solenoid valve 38 is opened to cause the evaporator 12 to perform a cooling function. At the same time the fan 17 is operated at high speed and the compressor 23 is operated at high speed. Under these conditions the system operates to afford maximum 45 cooling, both of the evaporators 11 and 12 performing their cooling functions at this time. The evaporator 12 will continue to perform its cooling function until either the temperature within the space 10 decreases to 40° or the pressure in the evaporator 12 decreases to 15 lbs. or the head pressure increases to 180 lbs. If any of these contingencies occur then the solenoid valve 38 is closed, the fan 17 is operated 50 at low speed and the compressor 23 is operated at low speed.

Assume now that the system is shut down as 55 illustrated in the drawing and that the temperature within the space 10 rises to 40°. Also 60 assume that the evaporator 11 has not defrosted and therefore it is impossible to open the solenoid valve 37. Since the evaporator 12 was placed on the defrosting cycle before the evaporator 11 was placed on the defrosting cycle the 65 evaporator 12 will become defrosted before the evaporator 11. Since the evaporator 11 cannot be placed in operation the temperature in the space 10 continues to rise and when it rises to 42° the solenoid valve 38 will open to cause 70 the evaporator 12 to perform a cooling function since at this time the evaporator 12 is defrosted. The compressor 23 is then operated at low speed and the fan 17 is operated at high speed. As soon as the evaporator 11 is defrosted the solenoid valve 37 will be opened to place the evap-

5 orator 11 in operation, the fan 13 will be operated at high speed and the compressor 23 will be operated at high speed. The system will then continue to operate in the normal manner until the temperature within the space 10 decreases to 38°.

Since the solenoid valves 37 and 38 cannot be opened and since the compressor 23 cannot be placed in operation unless the head pressure is below 140 lbs. the system is protected against 10 damage due to the failure of supply of condenser water. Also upon the occurrence of an overload condition in either the low speed or high speed circuits of the compressor motor the compressor is shut down. Since both solenoid 15 valves 37 and 38 are controlled by a single two-stage thermostat 50 the proper sequence of operation may at all times be assured and the control point of the thermostat may be easily raised or lowered without upsetting this sequence of operation.

If the head pressure cut-out setting of the controller 48 is set at, say, 180 lbs. and the head pressure cut-out setting of the controller 49 is set at, say, 185 lbs., then upon an increase in 25 head pressure to 180 lbs. only the relay 46 drops out, the other relay 47 remaining energized. Thus, the compressor is placed on low speed operation but if the head pressure increases to 185 lbs. then the relay 47 also drops out to 30 stop the compressor. Accordingly, if there should be only a partial failure in the supply of condensing water, the compressor may be placed on low speed operation and still some cooling may be accomplished.

Although for purposes of illustration one form of this invention has been disclosed, other forms thereof may become apparent to those skilled in the art upon reference to this disclosure and therefore this invention is to be limited only 40 by the scope of the appended claims.

I claim as my invention:

1. In a control system for a refrigerating apparatus having a plurality of evaporators for cooling a space, a condenser and a compressor 45 for circulating refrigerant through the evaporators, the combination of, a valve associated with each evaporator for controlling the flow of refrigerant therethrough, control means responsive to the temperature of the space for opening the valves upon a call for cooling to render their associated evaporators effective for performing a cooling function, and control means associated with each evaporator and responsive to the condition thereof for preventing 50 opening of the valve of that evaporator until that evaporator has defrosted.

2. In a control system for a refrigerating apparatus having a plurality of evaporators for cooling a space, a condenser and a compressor 60 for circulating refrigerant through the evaporators, the combination of, a valve associated with each evaporator and located between the evaporator and the low pressure side of the compressor for establishing and interrupting communication therebetween, control means responsive to the temperature of the space for opening the valves upon a call for cooling to render their associated evaporators effective for performing a cooling function, and control means 65 associated with each evaporator and responsive to the condition thereof for preventing opening of the valve of that evaporator until that evaporator has defrosted.

3. In a control system for a refrigerating ap-

paratus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the temperature of the space for opening the valves upon a call for cooling to render their associated evaporators effective for performing a cooling function, and control means associated with each evaporator and responsive to the pressure therein for preventing opening of the valve of that evaporator until the pressure therein has risen to a defrosting value.

4. In a control system for a refrigerating apparatus having a plurality of evaporators for cooling a space, a condenser and a compressor for circulating refrigerant through the evaporators, the combination of, a valve associated with each evaporator for controlling the flow of refrigerant therethrough, air circulating means associated with each evaporator for circulating air thereover, control means responsive to the temperature of the space for opening the valves and for controlling the air circulating means to increase the circulation of air over the evaporators upon a call for cooling to render their associated evaporators effective for performing a cooling function, and control means associated with each evaporator and responsive to the condition thereof for preventing opening the valve of that evaporator and increasing the circulation of air thereover until that evaporator has defrosted.

5. In a control system for a refrigerating apparatus having a plurality of evaporators for cooling a space, a condenser and a compressor for circulating refrigerant through the evaporators, the combination of, a valve associated with each evaporator for controlling the flow of refrigerant therethrough, air circulating means associated with each evaporator for circulating air thereover and operated at low speed or high speed, control means responsive to the temperature of the space for opening the valves and for operating the air circulating means at high speed upon a call for cooling to render their associated evaporators effective for performing a cooling function, and control means associated with each evaporator and responsive to the condition thereof for preventing opening of the valve of that evaporator and high speed operation of the air circulating means of that evaporator until that evaporator has defrosted.

6. In a control system for a refrigerating apparatus having a plurality of evaporators for cooling a space, a condenser and a compressor for circulating refrigerant through the evaporators, the combination of, a valve associated with each evaporator for controlling the flow of refrigerant therethrough, control means responsive to the temperature of the space for opening the valve upon a call for cooling to render their associated evaporators effective for performing a cooling function, control means associated with each evaporator and responsive to the condition thereof for preventing opening of the valve of that evaporator until that evaporator has defrosted, and means for operating the compressor at low speed when one of the valves is opened and for increasing the speed of operation of the compressor as more valves are opened.

7. In a control system for a refrigerating apparatus having a plurality of evaporators for cooling a space, a condenser and a compressor for circulating refrigerant through the evaporators, the combination of, a valve associated with each evaporator for controlling the flow of refrigerant therethrough, air circulating means associated with each evaporator for circulating air thereover, control means responsive to the temperature of the space for opening the valves and for controlling the air circulating means to increase the circulation of air over the evaporators upon a call for cooling to render their associated evaporators effective for performing a cooling function, control means associated with each evaporator and responsive to the condition thereof for preventing opening the valve of that evaporator and increasing the circulation of air thereover until that evaporator has defrosted, and means for operating the compressor at low speed when one of the valves is opened and for increasing the speed of operation of the compressor as more valves are opened.

8. In a control system for a refrigerating apparatus having a plurality of evaporators for cooling a space, a condenser and a compressor for circulating refrigerant through the evaporators, the combination of, a valve associated with each evaporator for controlling the flow of refrigerant therethrough, control means responsive to the temperature of the space for progressively opening the valves as the space temperature increases to render sequentially their associated evaporators effective for performing a cooling function, and control means associated with each evaporator and responsive to the condition thereof for preventing opening of the valve of that evaporator until that evaporator has defrosted.

9. In a control system for a refrigerating apparatus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the temperature of the space for progressively opening the valves as the space temperature increases to render sequentially their associated evaporators effective for performing a cooling function, and control means associated with each evaporator and responsive to the condition thereof for preventing opening of the valve of that evaporator until that evaporator has defrosted.

10. In a control system for a refrigerating apparatus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the temperature of the space for progressively opening the valves as the space temperature increases to render sequentially their associated evaporators effective for performing a cooling function, and control means associated with each evaporator and responsive to the pressure therein for preventing opening of the valve of that evaporator until the pressure therein has risen to a defrosting value.

11. In a control system for a refrigerating ap-

paratus having a plurality of evaporators for cooling a space, a condenser and a compressor for circulating refrigerant through the evaporators, the combination of, a valve associated with each evaporator for controlling the flow of refrigerant therethrough, control means responsive to the temperature of the space for progressively opening the valves as the space temperature increases to render sequentially their associated evaporators effective for performing a cooling function, control means associated with each evaporator and responsive to the condition thereof for preventing opening of the valve of that evaporator until that evaporator has defrosted, and means for operating the compressor at low speed when one of the valves is opened and for increasing the speed of operation of the compressor as more valves are opened.

12. In a control system for a refrigerating apparatus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the temperature of the space for opening the valves upon a call for cooling to render their associated evaporators effective for performing a cooling function, and control means associated with each evaporator and responsive to the pressure therein for preventing opening of the valve of that evaporator until the pressure therein has risen to a defrosting value and for closing the valve of that evaporator when the pressure therein decreases to a predetermined low value.

13. In a control system for a refrigerating apparatus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the temperature of the space for opening the valves upon a call for cooling to render their associated evaporators effective for performing a cooling function, control means associated with each evaporator and responsive to the pressure therein for preventing opening of the valve of that evaporator until the pressure therein has risen to a defrosting value, means for operating the compressor at low speed when one of the valves are opened and for increasing the speed of operation of the compressor as more valves are opened, and means for closing the valves and stopping operation of the compressor when the pressure on the low pressure side of the refrigerating apparatus decreases to a predetermined low value.

14. In a control system for a refrigerating apparatus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the temperature of the space for progressively opening the valves as the space temperature increases to render sequentially their associated evaporators effective for per-

forming a cooling function, control means associated with each evaporator and responsive to the pressure therein for preventing opening of the valve of that evaporator until the pressure therein has risen to a defrosting value, means for operating the compressor at low speed when one of the valves is opened and for increasing the speed of operation of the compressor as more valves are opened, and means for closing the valves and stopping operation of the compressor when the pressure on the low pressure side of the refrigerating apparatus decreases to a predetermined low value.

15. In a control system for a refrigerating apparatus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the pressure on the high pressure side of the refrigerating apparatus for preventing opening of the valves upon a call for cooling to render their associated evaporators effective for performing a cooling function, control means associated with each evaporator and responsive to the pressure therein for preventing opening of the valve of that evaporator until the pressure therein has risen to a defrosting value, and means responsive to the pressure on the high pressure side of the refrigerating apparatus for preventing opening of the valves until the pressure decreases to a predetermined low value.

16. In a control system for a refrigerating apparatus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the temperature of the space for opening the valves upon a call for cooling to render their associated evaporators effective for performing a cooling function, control means associated with each evaporator and responsive to the pressure therein for preventing opening of the valve of that evaporator until the pressure therein has risen to a defrosting value, and means responsive to the pressure on the high pressure side of the refrigerating apparatus for preventing opening of the valves until the pressure decreases to a predetermined low value.

17. In a control system for a refrigerating apparatus having a plurality of evaporators for cooling a space, a condenser and a compressor for circulating refrigerant through the evaporators, the combination of, a valve associated with each evaporator and located between the evaporator and the low pressure side of the compressor for establishing and interrupting communication therebetween, control means responsive to the temperature of the space for opening the valves upon a call for cooling to render their associated evaporators effective for performing a cooling function, control means associated with each evaporator and responsive to the pressure therein for preventing opening of the valve of that evaporator until the pressure therein has risen to a defrosting value, means for operating the compressor at low speed when one of the valves is opened and for increasing the speed of operation of the compressor as more valves are opened, and means for closing the valves and stopping operation of the compressor when the pressure on the low pressure side of the refrigerating apparatus decreases to a predetermined low value.

valves is opened and for increasing the speed of operation of the compressor as more valves are opened, and means responsive to the pressure on the high pressure side of the refrigerating apparatus for preventing opening of the valves and for preventing starting of the compressor until the pressure decreases to a predetermined low value.

18. In a control system for a refrigerating apparatus having evaporator means, a compressor for circulating refrigerant through the evaporator means and a multispeed motor for operating the compressor, the combination of, means for completing a low speed circuit to the compressor motor for operating the compressor at low speed, means for completing a high speed circuit to the compressor motor for operating the compressor at high speed, means including overload cutout means responsive to the current flow in the low speed circuit and the high speed circuit for stopping the compressor motor when an overload condition occurs in either circuit, and means for preventing restarting of the compressor motor until the pressure on the low pressure side of the refrigerating apparatus increases to a predetermined high value.

19. In a control system for a refrigerating apparatus having evaporator means, a compressor for circulating refrigerant through the evaporator means and a multispeed motor for operating the compressor, the combination of, means for completing a low speed circuit to the compressor motor for operating the compressor at low speed, means for completing a high speed circuit to the compressor motor for operating the compressor at high speed, means including overload cut-out means responsive to the current flow in the low speed circuit and the high speed circuit for stopping the compressor motor when an overload condition occurs in either circuit, and means for preventing restarting of the compressor motor until the pressure on the high pressure side of the refrigerating apparatus decreases to a predetermined low value.

20. In a control system for a refrigerating apparatus having a plurality of evaporators and a multispeed motor driven compressor for the evaporators, a valve associated with each evaporator for controlling the flow of refrigerant therethrough, control means responsive to the demands on the refrigerating system for opening said valves to render their associated evaporators effective, means for completing a low speed circuit to said compressor motor when only one of said valves is open, means for completing a higher speed circuit to said compressor motor when more than one of said valves is open, means including overload cut-out means responsive to the current flow in the low speed circuit and the higher speed circuit for stopping the compressor motor when an overload condition occurs in either circuit, and means for preventing open-

ing of any valve until the suction pressure on its evaporator rises to a predetermined value whereby said compressor motor cannot be restarted after it is stopped by an overload condition until the low side pressure on at least one of said evaporators has risen to said predetermined value. 5

21. In a control system for a refrigerating apparatus having a plurality of evaporators and a multispeed motor driven compressor for the evaporators, a valve associated with each evaporator for controlling the flow of refrigerant therethrough, control means responsive to the demands on the refrigerating system for opening said valves to render their associated evaporators 15 effective, means for completing a low speed circuit to said compressor motor when only one of said valves is open, means for completing a higher speed circuit to said compressor motor when more than one of said valves is open, means including overload cut-out means responsive to the current flow in the low speed circuit and the higher speed circuit for stopping the compressor motor when an overload condition occurs in either circuit, and means for preventing opening 20 of any valve unless the head pressure of the refrigerating apparatus is below a predetermined value whereby said compressor motor cannot be restarted after it is stopped by an overload condition until the head pressure of the refrigerating apparatus has fallen to said predetermined value. 25

22. In a control system for a refrigerating apparatus having a plurality of evaporators for cooling a space and a multispeed motor driven compressor for the evaporators, a valve associated with each evaporator for controlling the flow of refrigerant therethrough, control means responsive to the temperature of a space for opening said valves to render their associated 35 evaporators effective when the space temperature rises, means for completing a low speed circuit to said compressor motor when only one of said valves is open, means for completing a higher speed circuit to said compressor motor when more than one of said valves is open, means including overload cut-out means responsive to the current flow in the low speed circuit and the higher speed circuit for stopping the compressor motor when an overload condition occurs in 40 either circuit, and means for preventing opening of any valve until the suction pressure on its evaporator rises to a predetermined value and the head pressure on the system falls to a predetermined value whereby said compressor motor 45 cannot be restarted after it is stopped by an overload condition until the low side pressure on at least one of said evaporators has risen to said predetermined value and the head pressure on the system has lowered to its predetermined 50 value. 55

ALWIN B. NEWTON.

CERTIFICATE OF CORRECTION.
Patent No. 2,229,301.

January 21, 1941.

ALWIN B. NEWTON.

It is hereby certified that error appears in the printed specification of the above numbered patent requiring correction as follows: Page 8, second column, line 23, claim 15, strike out "side of the refrigerating apparatus for prevent--" and insert instead the syllable and words --sive to the temperature of the space for opening--; and that the said Letters Patent should be read with this correction therein that the same may conform to the record of the case in the Patent Office.

Signed and sealed this 25th day of March, A. D. 1941.

(Seal)

Henry Van Arsdale,
Acting Commissioner of Patents.
